UNITED STATES PATENT OFFICE

JOHN W. SPRY, OF DALLAS, TEXAS

APPARATUS FOR PROPORTIONING AND MIXING MATERIALS FOR CONCRETE

Application filed August 19, 1929. Serial No. 387,004.

This invention relates to an apparatus for proportioning and mixing materials for concrete.

The primary purpose of this invention is to provide an apparatus whereby the materials for concrete may move by gravity through the necessary measuring devices, weighing devices, and mixing devices in an expeditious manner.

It is also an object of the invention that the loading of trucks with the mixed materials may be accomplished by gravity; and that the arrangements permit relatively quick loading and exit of the trucks.

It is also within the scope of the objects of the invention that the apparatus be so simplified in arrangement and operation that there will occur a considerable saving in labor over that necessary for operating the apparatus now commonly employed for the same purpose.

Other objects, and objects relating to details of construction and arrangement of units and parts will appear in the detailed description to follow.

In the drawings:

Figure 1 is a top plan view of the apparatus constructed in accordance with the present invention.

Figure 2 is a vertical sectional view taken through the apparatus substantially on the line 2-2 of Figure 1.

Figure 3 is a view similar to Fig. 2 taken substantially on the line 3-3 of Figure 1.

Figure 4 is a fragmentary sectional view illustrating a bin or compartment.

Figure 5 is a perspective detail view illustrating a weighing receptacle and outlet therefor.

Figure 6 is a top plan view of a modified form of the apparatus.

Figure 7 is a view partly in elevation and partly in vertical section of the same, and

Figure 8 is a detail perspective view of an extensible chute.

Referring to the drawings, 10 designates generally a pit which is formed by end walls 12 and side walls 13. The walls forming the pit are preferably of reinforced concrete. Each wall is inclined and converges toward

the bottom of the pit whereby materials dumped into the pit will gravitate toward the center thereof. The pit is formed with a division wall 14 for providing the two compartments 10' and 11'.

The central and bottom portion of the wall 14 is formed with a bulge 15' on each side thereof to provide a housing 15 for a container 16. The container 16 has communicating therewith a vent pipe 17 and a feed pipe 18 which terminates at its outer end in a hopper 19.

Centrally of the pit are provided four pillars or posts which are arranged in pairs, two being placed on each side of the wall 14 as shown at 20 and 21, respectively. Upon each pair of pillars there is seated an I-beam 22 upon which rests I-beams 23 that support rails 24. The rails 24 may be further supported by suitable concrete blocks 25'.

As best shown in Figs. 2 and 3, the pillars 20 and 21 are extended considerably below the bottom of the pit 10. The necessary excavations are made to permit trucks to pass beneath the pit 10. For this purpose a roadbed 25 is provided which is preferably of reinforced concrete. As shown in Figs. 2 and 3 the roadbed extends between the pillars 20 and pillars 21, and each end thereof terminates in an inclined section 26 which is provided with suitable retainer walls 27.

At a suitable distance above the roadbed 25 I provide a platform 28 which may be supported by the pillars 20 and 21. The platform 28 has constructed therewith a loading funnel 29 which is located at a suitable point for discharging materials into the receiving body of a truck as indicated at 30.

The platform 29 also supports a mixer 31 which is adapted to discharge the materials mixed thereby into the funnel 29. The mixer 31 is provided with a hopper 32, above which there are arranged three spouts 33, all of which are adapted to discharge materials into the hopper 32. The spouts 33 may be supported in any convenient manner as by suitable brackets or supports (not shown) extending from the pillars 20 and 21. Each spout 33 is in register with a weighing receptacle 34 and each weighing receptacle reg-

isters with an outlet pipe 35. The outlet pipes communicate with the compartments 10' and 11' and the container 16.

In Figure 5 I have shown the specific structure of a weighing receptacle 34. As is seen the receptacle is cylindrical and pivotally supported by a bifurcated arm 36. The arm 36 extends from a scale (not shown) of suitable construction which may be supported in any convenient manner by the pillars 20 and 21. Each receptacle 34 terminates at its lower end in a reduced portion 37 which is provided with a closure plate or gate 38 hinged to an operating lever 39. The lever 39 is pivoted, as at 40, and adapted to swing over a quadrant 41. The lever arm 39 carries a thumb screw whereby said lever may be locked against swinging movement.

Each outlet pipe 35 is provided with a plate closure or gate 42 and an operating handle 43. The structure of the gate 42 and operating handle therefor is the same as utilized for the weighing receptacles 34.

It should be noted that the pillars 20 and 21 are supported by suitable concrete bases 44 and that the roadbed 25 may be provided with a drain pipe, as at 45.

In utilizing my apparatus for mixing materials for concrete, gravel may be dumped into the compartment 11' and sand into compartment 10' from a car on the rails 24. Cement may be dumped into the hopper 19 for filling the container 16. The amount of materials desired may be obtained from the outlets 35, weighed in the receptacles 34, mixed by the mixer 31, and then permitted to discharge through funnel 29 into the dump-body of a waiting truck. As is clearly apparent the apportioning, mixing, and loading of the materials can be accomplished with a minimum of labor and time. Also, it is apparent that the apparatus would not need repair and could be operated at a relatively low cost.

Now, referring to Figs. 6 to 8, inclusive, I have shown a pit divided by a central wall 46 for providing two compartments 47 and 48. The pit is constructed similar to that shown in Figs. 1 to 4, inclusive. The division wall 46 is constructed for providing a housing 49 for the cement container or bin 50. The container is provided with a vent pipe 51 and a feed pipe 52. In order to elevate the materials for mixing and loading, I provide two tracks 53 and 53' which are arranged as shown with relation to the compartments 47 and 48 and cement container or bin 50. Suitable dump-cars 54 and 54' are provided, each being connected to one end of a cable 55, the other end of each cable being connected to a drum which may be driven by an electric motor or the like.

Either car 54 or 54' may be brought to a position beneath the chutes 55 as illustrated in Fig. 7. Each chute is in register with a weighing receptacle 56 which in turn regis-

ters with an outlet pipe 57. The weighing receptacles and outlet pipes are provided with hand-lever operated gates of the construction shown in Fig. 5.

The chutes 55 are constructed as specifically shown in Fig. 8. Each chute comprises telescopic pipe sections 58 and 59, the section 59 being supported for universal movement through a bracket 60 and ball and socket joint 61. The upper end of section 59 is formed with an outwardly flared lip 62 to facilitate the reception of material from the associated weighing receptacle 56. The section 58 is provided with handles 63 and an apertured ear 64 to which is connected one end of a cable 65, said cable passing over a pulley 66 and having secured to its other end a suitable counterweight 67.

The upper ends of tracks 53 and 53' are supported by a suitable frame structure 68, and forward to this frame there is provided a platform 69 beneath which a truck may pass as shown. The platform 69 supports a mixer 70 having a hopper 71 in register with a chute 72 into which the materials may be dumped from the cars 54 and 54'. It will be understood that the materials mixed by the mixer 71 can be discharged into the receiving body of a truck beneath the platform 69.

In utilizing the apparatus shown in Figs. 6 to 8, inclusive, one of the cars 54-54' is brought to the position shown in Fig. 7 and an operator grasps the chutes 55 and swings or lowers them to the desired position for discharging into the car. The operator can now obtain from the outlet pipes 57 the amount of gravel, cement, and sand desired, weigh the materials in the receptacles 56 and discharge them through the chutes 55 into the car therebeneath. As is obvious the chutes 55 can be easily and quickly arranged or adjusted for discharging materials into a car on either track. After the desired amount of materials are discharged into a car, the car is drawn to the upper end of the track and dumped into chute 72 which delivers the materials into the mixer-hopper 71. After the materials are mixed they are dumped into the receiving body of the truck beneath the platform 69.

I claim:

1. A gravity feed concrete mixing apparatus or plant comprising a pit divided into compartments with inclined walls to direct materials therein to flow toward the center of the pit, a container between the compartments, a mixer hopper beneath the center of the pit, vertically disposed outlet pipes whereby materials may be discharged from each of said compartments and the container into said hopper, and a loading funnel beneath the mixer hopper.

2. A gravity feed concrete mixing apparatus or plant comprising a pit divided into compartments with inclined walls to direct

materials therein to flow toward the center of the pit, a container between the compartments, a mixer hopper beneath the center of the pit, vertically disposed outlet pipes whereby materials may be discharged from each of said compartments into said hopper, a loading funnel beneath the mixer hopper, and a roadway beneath the loading funnel whereby the mixed materials may be discharged into the receiving body of a vehicle.

10. 3. A concrete material mixing apparatus comprising a pit and a central division wall to provide two compartments, the walls of which are inclined to cause materials therein to flow toward the division wall, a container within the division wall, a hopper beneath the pit, and pipe outlets whereby materials from each of the compartments and container may be discharged into said hopper.

20. 4. A concrete material mixing apparatus comprising a pit and a central division wall to provide two compartments, the walls of which are inclined to cause materials therein to flow toward the division wall, a container within the division wall, a hopper beneath the pit, pipe outlets whereby materials from each of the compartments and container may be discharged into said hopper, and weighing receptacles between the outlet pipes and hopper.

30. 5. A concrete material mixing apparatus comprising a pit and a central division wall to provide two compartments, the walls of which are inclined to cause materials therein to flow toward the division wall, a container within the division wall, a feed spout for said container, a hopper beneath the pit, and pipe outlets whereby materials from each of the compartments and container may be discharged into said hopper.

40. 6. A concrete material mixing apparatus comprising a pit and a central division wall to provide two compartments, the walls of which are inclined to cause materials therein to flow toward the division wall, a container within the division wall, weighing devices, a mixer, valve-controlled pipe outlets whereby materials may be discharged from each compartment and from the container into the weighing devices, means for delivering the materials from the weighing devices into the mixer, and a roadway beneath the mixer whereby the mixed materials may be deposited into a vehicle body for conveyance.

50. 7. In a concrete mixing apparatus, a pit having inclined walls and provided with a partition dividing it into two compartments, one for sand and the other for gravel, a container for cement housed in the partition, the container having a feed pipe extending out through one side of the pit and a vent pipe extending out through the top of the partition.
